UNITED STATES PATENT OFFICE.

JOSEPH V. PETRELLI, OF NEW HAVEN, CONNECTICUT.

REVERSING MECHANISM.

1,239,213.

Specification of Letters Patent. Patented Sept. 4, 1917.

Application filed June 8, 1914. Serial No. 843,725.

To all whom it may concern:

Be it known that I, JOSEPH V. PETRELLI, a citizen of the United States, residing at New Haven, in the county of New Haven and State of Connecticut, have invented a new and useful Improvement in Reversing Mechanism; and I do hereby declare the following, when taken in connection with the accompanying drawings and the characters of reference marked thereon, to be a full, clear, and exact description of the same, and which said drawings constitute part of this application, and represent, in—

Figure 1 a view in side elevation of my improved reversing mechanism, shown as set for reversing.

Fig. 2 a plan view of the mechanism also shown as set for reversing.

Fig. 3 a corresponding plan view of the mechanism shown as set for going ahead.

Fig. 4 a view of the mechanism in longitudinal vertical section, shown as set for going ahead.

Fig. 5 a view of the mechanism in vertical transverse section on the line *a*—*b* of Fig. 4 and looking inward toward the inner member of its two-part case.

Fig. 6 a view of the mechanism in front elevation with the lower portion of the outer member of its two-part case broken away, and also with the outermost steel friction-disk broken away to expose the outermost bronze friction-disk.

Fig. 7 a view of the mechanism in transverse central section.

Fig. 8 a detached view on a reduced scale, of one of the steel friction-disks.

Fig. 9 a corresponding view of one of the bronze friction-disks.

Fig. 10 a detached, rear perspective view of the combined driving-sleeve and gear-cage.

Fig. 11 a view thereof in longitudinal section through the centers of two of the four webs which unite its washer-like flanges.

My invention relates to an improvement in that class of reversing mechanisms primarily designed for use in motor boats, but adapted to be used in automobiles, in conjunction with stationary shafting, and in fact, in many situations calling for the transmission of motive power, the object being to produce a simple, reliable, durable and compact mechanism in which the danger of breakage is reduced to the minimum by removing the strain from the gear teeth

when the mechanism is set for going ahead, and in which provision is made for reversing at the full speed.

With these ends in view my invention consists in a reversing mechanism having certain details of construction and combinations of parts as will be hereinafter described and pointed out in the claims.

In carrying out my invention as herein shown, I employ a combined driving-sleeve and gear-cage consisting of a sleeve 2, parallel circular flanges 3, 4, and four integral, heavy webs 5 placed quartering between the said flanges and uniting the same. The said sleeve 2 is formed with an internal key-way 6, whereby the driving or engine-shaft, which is not shown, may be locked into it.

At its inner end, the said driving-sleeve 2 is formed with a concentric interior recess 7 containing a bushing 77 for the reception of the reduced inner end of the driven sleeve 8 which is provided at its outer end with a key-way 9 for the reception of the key 10 of the driven-shaft 11 which abuts against the engine-shaft which, as stated, is not shown. The driven-shaft 11 is held against longitudinal displacement in the driven-sleeve 8 by means of a set screw 12 in the extreme outer end thereof. A corresponding screw 13 is mounted in the driving-sleeve 2 for holding the engine-shaft against longitudinal movement therein.

My improved mechanism is provided with a two-part case consisting of an outer cover-like or flanged case-member 14 and a corresponding inner cover-like or flanged case-member 15. The said case-member 14 is mounted upon the driving-sleeve 2 from which it is separated by a bushing 16, while the case-member 15 is mounted upon the outer end of the driven-sleeve 8 from which it is separated by a bushing 17.

The said case-members 14 and 15 are located upon the opposite sides of an internal gear 18 provided with a circumferential, centralizing or positioning-rib 19 against the opposite faces of which the edges of the flanges of the said case-members 14 and 15 abut, as clearly shown in Fig. 4. The said case-members and internal gear are secured together, so as to function as a unit, by means of a series of long assembling bolts 20 furnished at their ends with nuts 21. These bolts pass through suitable holes 22 formed for their reception near the edges of the case-members 14 and 15 and through corre-

sponding holes 23 formed in the circumferential rib 19 of the internal gear 18. The outer face of the said rib 19, is engaged by the central portion of the inner face of a brake-band 24 the edges of which are set into circumferential recesses 25 in the outer faces of the flanges of the case-members 14 and 15. The said brake-band 24 is formed at its respective ends with two lugs 26 mounting an operating bolt 27 provided at one end with a nut 28 and having its opposite end formed with a longitudinal slot 29 for the reception of a small toggle-lever 30 hung upon a pin 31 and carrying a stop-pin 32 in the shorter of its two arms. The longer arm of this lever, has a knuckle-like terminal 33 which co-acts with a semi-circular recess 34 in the outer edge of the free outer end of an operating-lever 35 which passes through the slot 29 in the bolt 27 at a point between the said toggle-lever 30 and a segmental rocking-shoe 36 set into a curved recess 37 formed in the outer face of the adjacent lug 26 of the brake-band 24. The outer end of the said lever 35 is provided with a stop-pin 38 which engages with the outer face of the bolt 27 and prevents the toggle-lever 30 from being drawn beyond its center. The inner end of the said lever 35, is secured by a stud 39 to the arm 40 of a yoke 41 setting over the outer end of a cone 42 sliding upon the driven-shaft 11. At its outer end the said cone 42 is formed with an annular recess 43 containing a split-collar 44 receiving the studs 45 by means of which the yoke is connected with the cone. The arm 40 of the yoke 41 is formed with a recess 46 for the reception of the rear end of a bowed fulcrum-arm 47 pivotally secured to it by a stud 48 which is located between the inner end of the lever 35 and the yoke 41. In other words, the fulcrum-arm is pivotally connected to the handle of the reversing mechanism at a point between the connection of the operating-lever with the handle and the center on which the handle swings, *i. e.*, the pivot of the yoke. The upper end of the said arm 47 is inserted between the two up-standing lugs 26 aforesaid, and is split and bored for the reception of the operating-bolt 27 upon which the arm is clamped by a bolt 78 (Fig. 4). The said arm 40 of the yoke 41 is slotted for the reception of a handle 49 secured in place by rivets 50.

Under the construction just above described, when the handle 49 is drawn forward into the go-ahead position as shown in Fig. 4, the brake-band 24 expands by its own resiliency so as to impose no restraint upon the free rotation, as a unit, of the case-members 14 and 15 and the internal gear 18.

On the other hand, when the handle 49 is pushed rearward into the reversing posi-

tion, shown by Figs. 1 and 2, the operating-lever 35 co-acts with the toggle-lever 30 which, as it turns upon its pivot 31, forces the lever 35 laterally inward against the shoe 36 and contracts the brake-band 24 by forcing the lug 26 carrying the shoe 36, toward the other lug 26 at the opposite end of the brake-band 24, whereby the case-members 14 and 15 and the internal gear 18 are firmly gripped and held against rotation by the brake-band 24 which is the permanently stationary member of the entire mechanism and thereto provided with horizontal installation arms 51 by means of which the mechanism is supported in place.

When the handle 49 is drawn forward into its go-ahead position, the cone 42 co-acts with the inwardly turned outer ends of three cam-like go-ahead levers 52 respectively mounted in three pairs of radially arranged lugs 53 on a lever-carrying ring 54 mounted upon a concentric hub 55 formed upon the rear face of the inner case-member 15 and adjustably secured in place thereupon by means of a threaded take-up ring 56 having peripheral adjusting-notches 57 receiving a locking-finger 58 secured by a screw 59 to the lever-carrying ring 54 as shown in Figs. 4 and 5. The said levers 52 turn upon studs 60 mounted in the lugs 53 aforesaid.

The cam-like heels of the said go-ahead levers 52 co-act with the rounded outer ends of the stems 61 of three disk-like pressure-plungers 62 located in circular recesses 63 formed in the inner face of the case-member 15.

The said pressure-plungers 62 are relied upon to bring into play two sets of steel friction-disks 64 and bronze friction-disks 65 arranged in alternation and provided for normally coupling the driving-sleeve 2 with the driven-sleeve 8 through the intermediary of the case-members 14 and 15 and the internal gear 18, when the mechanism is adjusted for going ahead at which time, by virtue of the employment of the said two sets of friction-disks, all strain is removed from the teeth 79 of the internal gear 18, the teeth of the outer intermediate pinions 66, the teeth of the inner intermediate pinions 67, and the teeth of the driven-gear 68 which is fixed by a key 69 upon the driven-sleeve 8. The toothed elements just enumerated, of my improved mechanism, are subject to no strain whatever when the mechanism is set for going ahead.

The steel friction-disks 64 (Fig. 8) are in part mounted upon the driving-sleeve 2 and in part upon the driven-sleeve 8, while the bronze friction-disks 65 (Fig. 9) are in part mounted in the outer case-member 14 and in part in the rear case-member 15.

For insuring the rotation of the steel friction-disks 64 with the driving-sleeve 2 and the driven-sleeve 8, the said disks are formed

with internal locking-notches 70 receiving a circular series of radial locking-ribs 71, formed upon the periphery of the said sleeves, respectively, as shown in Figs. 4 5 and 6.

For insuring the rotation of the bronze friction-disks 65 with the case-members 14 and 15, the said disks are provided with a circular series of peripheral locking-notches 10 72 receiving correspondingly arranged inwardly projecting locking-lugs 73 (Fig. 6) formed upon the inner faces of the flanges of the said case-members 14 and 15.

The steel friction-disks 64 though coupled 15 for rotation with the said sleeves 2 and 8, are free to be moved laterally with respect thereto within narrow limits, while the bronze friction-disks 65 though compelled to rotate with the case-members 14 and 15, 20 are allowed to have a slight lateral play with respect thereto. The described lateral movement of the two sets of disks is provided for, so that they may be cut into and out of action by means of the pressure plungers 62 and the cam-like go-ahead levers 52 already described.

When the handle 49 is thrown forward as shown in Fig. 4, the cone 42 is moved rearward and the go-ahead levers 52 brought 25 into play for forcing the pressure-plungers 62 forward, whereby the set of friction-disks within the case-member 15 are directly compressed and also whereby the set of friction-disks in the case-member 14 are compressed by the rearward movement of the 30 entire case and internal gear 18, which parts are drawn inward as a unit by the reverse force set up between the stems 61 of the plungers 62 and the pivots 60 of the levers 40 52, causing the friction-disks in the outer case-member 14 to be crowded rearward against the outer face of the flange 3 of the gear-cage.

The outer intermediate pinions 66 are 45 mounted upon studs 75 supported at their opposite ends in the flanges 3 and 4 of the gear-cage, while the inner intermediate pinions 67 are mounted upon studs 76 also supported at their ends in the said flanges 3 and 50 4 of the gear-cage. It is to be particularly noted that all of the pinions employed are mounted in the gear-cage which is virtually a part of the driving-sleeve 2. The said pinions therefore are directly connected 55 through the gear-cage with the source of power. It is to be further noted that on account of having two sets of interposed pinions mounted in the gear-cage, a reversal of the driven sleeve 8 results from stopping the 60 rotation of the internal gear 18 by the application of the brake-band 24.

It will be understood from the foregoing description that by pulling the handle 49 forward, the two sets of friction-disks 64 65 and 65 are brought into play for coupling

the driven-sleeve 8 to the driving-sleeve 2 in such a manner that no strain whatever is allowed to fall upon any of the gear teeth of the mechanism during the "forward drive," whereby the breakage of the teeth 70 is prevented altogether and the wear of the gear teeth is reduced to the minimum and confined entirely to the period of reversal. When the mechanism is set for going a head, all of its elements rotate except 75 the brake-band 24, the lever 35, the link 47, the handle 49 and the yoke 41. When the handle 49 is thrown rearward into its reversing position, the cone 42 is pushed forward so as to release the go-ahead levers 52, 30 whereby the two sets of friction-disks are immediately relieved of all pressure and thus cut out of play. At the same time, the brake-band 24 is brought into play for gripping the two case-members 14 and 15 35 and the internal gear 18 which are thereafter held against rotation. Now when the gear-cage rotates as it always does with the driving-sleeve 2, the outer and inner intermediate pinions 66 and 67 operating upon 40 each other and upon the stationary internal gear 18, will cause the driven-sleeve 8 to rotate at the same speed at which it rotated previously but in the opposite direction. At this time, the steel friction-disks 64 which 45 are non-rotatably connected with the two sleeves, will rotate between the bronze friction-disks 65 which will remain at rest with the respective inner and outer case-members 50 14 and 15.

In the intermediate position of the handle 49, the said friction-disks 64 and 65 are not clamped upon each other and brought into play, nor is the brake-band 24 clamped upon the internal gear 18 and brought into play, 55 from which it follows that the driving-sleeve 2 revolves the case-members, gear-cage and internal gear idly and without transmitting any power to the driven-gear which, being uncoupled from the driving-sleeve, remains 60 at rest.

I also wish to point out that all of the connections of the handle with the friction-band are located entirely above the center or axis of the mechanism, and therefore in 65 positions where they are readily accessible for examination and adjustment.

When the mechanism is set for going ahead, the driving-sleeve 2 and the driven-sleeve 8 revolve together by virtue of being 120 coupled together by means of the two sets of friction-disks which are clamped upon the opposite faces of the two-part case. At this time the pinions carried by the gear-cage will not only be idle, but relieved of 125 strain. They will revolve, of course, with the cage but have no revolution upon their own axes. On the other hand, when the mechanism is set for reversing, the brake-band holds the two-part case and internal 130

gear against rotation, and as the pressure is now removed from the friction-disks the gear-cage rotates within the internal gear with the effect of rotating the pinions carried thereby upon their respective axes and causing the driven-sleeve to be rotated at the same rate as the driving-sleeve but in the opposite direction from the rotation thereof. It will be understood that the driven-sleeve 10 then revolves within the bushings 77 and 17 between the driven-sleeve and the case-members 14 and 15.

I wish to particularly point out that by uniting the respective flanges 3 and 4 of 15 the gear-cage by the heavy integral webs 5, the torsional strain to which the flanges are subjected, is not communicated to the studs 75 upon which the intermediate pinions 66 and 67 are mounted, whereby the 20 alinement of the said pinions is maintained. I also wish to point out that by locating separate sets of friction disks or equivalent friction surfaces or friction means at the 25 respective ends of the gear-cage, the same is frictionally held within the case at both of its ends, whereby its driving power is increased and the back-lash which occurs if it is frictionally held only at one end, is avoided.

30 I claim:—

1. In a reversing mechanism, the combination with a case, of an internal gear rigidly connected therewith, a gear-cage located within the said case and comprising 35 inner and outer flanges one of which is formed with an outwardly projecting hub adapted to be rigidly connected with a source of power, a driven gear, pinions carried by the said cage, located between the 40 flanges thereof and interposed between the said internal gear and the said driven gear, friction means co-acting with the cage and the case, whereby the case and cage are constantly driven in the same direction for the forward drive and the cage for the reverse drive, and means for holding the said case and hence the said internal gear, against rotation, whereby the pinions are caused to 45 reversely rotate the driven gear, and hence the driven member, on the reverse drive.

2. In a reversing mechanism, the combination with a case, of an internal gear carried thereby, a gear-cage located within the 55 said case and comprising inner and outer flanges one of which is formed with an outwardly projecting hub adapted to be rigidly connected with a source of power, a driven gear, pinions carried by the said cage located between the flanges thereof and interposed 60 between the said gears, and friction means between the ends of the cage and the case, whereby the cage is constantly driven in the same direction for the forward drive and for the reverse drive, and whereby the forward drive of the mechanism is mainly car-

ried by the said friction means rather than by the gearing when interlocked.

3. In a reversing mechanism, the combination with a case, a gear-cage located within the case, a driving member rigidly connected with the gear-cage for constantly rotating the same in one direction and adapted to be solidly connected with the motive power, a driven member, two sets of friction disks respectively interposed between the gear-cage and case with which the disks are coupled for the rotation of the 70 said case and cage, one set of disks being coupled both with the said gear-case and the said gear-cage, and the other set being 75 coupled both with the said gear-case and the said driven member, and means for simultaneously imposing pressure upon both sets of disks and the ends of the gear-cage, whereby the gear-case is mainly held against 80 rotation by the said disks during the forward drive and the strain removed from the 85 gearing.

4. In a reversing mechanism, the combination with a case, of a driving and a 90 driven member, the latter being adapted to be solidly connected with the source of motive power, a gear-cage located within the case, rigidly connected with the said driving-member and carrying pinions, two sets 95 of friction disks respectively connected with the said driving and driven members for rotation therewith, two sets of friction disks connected with the case for rotation therewith, and arranged in alternation with the disks connected with the said driving and driven members, and means for applying inward pressure to the said disks thus causing the driving and driven members, the case, and the gear-cage to revolve together in the 100 same direction for the forward drive.

5. In a reversing mechanism, the combination with a case, an internal gear carried thereby, a gear-cage located within the said case, a driving member rigid with the gear-cage, projecting outward through the said case and adapted to be solidly attached to a source of power, a driven-member concentric with the gear-cage, a driven-gear carried by the driven-member, two sets of pinions carried by the gear-cage, meshing into each other and interposed between the said internal gear and the said driven gear, and two sets of friction disks interposed 110 between the ends of the case and the cage and constructed and arranged to frictionally couple together the driving and driven-members and the said case during the forward drive and so relieve the strain upon 115 the gearing.

6. In a reversing mechanism, the combination with a case, of an internal gear rigid therewith, a gear-cage located in the said case, pinions carried by the said cage, a driving member rigid with the said cage and 120

projecting outward through the said case for solid connection with the source of motive power, whereby the cage and internal gear are constantly driven in the same direction for the forward drive, a driven member, a driven-gear connected therewith and meshed into by the said pinions which are interposed between it and the said internal gear, two sets of friction disks respectively interposed between the ends of the case and the ends of the cage, one set of disks being

10

alternately connected with the case and the driven member, and means for holding the case and hence the internal gear against rotation, whereby the pinions are caused to reversely rotate the driven gear and hence the driven-member.

15 In testimony whereof, I have signed this specification in the presence of two subscribing witnesses.
